UNITED STATES PATENT OFFICE.

HERMAN ALBERT WILL, OF SHIRLEY, ILLINOIS.

WRENCH.

1,287,544.

Specification of Letters Patent. Patented Dec. 10, 1918.

Application filed May 6, 1918. Serial No. 232,851.

To all whom it may concern:

Be it known that I, HERMAN ALBERT WILL, a citizen of the United States, residing at Shirley, in the county of McLean, State of Illinois, have invented a new and useful Wrench; and I do hereby declare the following to be a full, clear, and exact description of the invention, such as will enable others skilled in the art to which it appertains to make and use the same.

The present invention relates to certain new and useful improvements in wrenches, and has for its object to provide a device of this character which embodies novel features of construction whereby the movable jaw can be quickly adjusted and held in an adjusted position without the loss of time which is incident to manipulating a screw member.

Further objects of the invention are to provide a wrench of this character which is comparatively simple and inexpensive in its construction, which is not liable to break or get out of repair, which can be quickly manipulated, and which can be collapsed into a small amount of space so as to be carried in the pocket without difficulty.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawings, in which:

Figure 1 is a side elevation of a wrench constructed in accordance with the invention, showing the same as collapsed and in position for carrying in the pocket or packing away in the tool chest.

Fig. 2 is a side elevation of the wrench when in operative position, portions being broken away and shown in section to illustrate more clearly the details of construction.

Fig. 3 is an end view of the two jaws of the wrench, showing the same as separated, the lower end of the handle being broken away.

Fig. 4 is an edge view of the lower end of the tubular stock and upper end of the handle extension, showing the spring latch member for locking the handle extension in an extended position.

Fig. 5 is a transverse sectional view on

the line 5—5 of Fig. 2, showing the end of the tubular stock.

Corresponding and like parts are referred to in the following description and indicated in all the views of the drawings by the same reference characters.

Referring to the drawings, which illustrate one embodiment of the invention, the numeral 1 designates a comparatively short tubular stock which has a fixed jaw 2 rigidly applied to one end thereof. A handle 3 is slidably mounted within the tubular stock 1, being adapted to be completely housed therein when the tool is collapsed, as indicated by Fig. 1, or to be moved outwardly so as to project beyond the stock when the tool is in use, as indicated by Fig. 2. One side of the tubular stock is provided at the end thereof with a slot within which a spring latch arm 4 is fitted, the upper end of the latch arm being secured to the stock by a suitable fastening member 5, while the lower end of the latch arm terminates in an inwardly projecting nose 6 which is adapted to engage a selected one of a series of openings 7 in the handle 3. The body portion of the latch arm 4 is flush with the outer surface of the stock 1 so as to avoid exterior projections, although an intermediate portion of the latch arm is crimped outwardly at 4^a to provide a finger piece which can be engaged by the fingers when it is desired to spring the latch arm outwardly and move the nose 6 into inoperative position. It will thus be obvious that the handle 3 can either be telescoped into the tubular stock and housed therein, or locked in a position projecting from the stock so as to be used as a handle, as indicated by Fig. 2. The end of the handle 3 may be sharpened as indicated at 8 so as to be susceptible of being used as a screw driver, if desired.

A movable jaw 9 is slidably mounted upon the stock 1, being shown as formed with a sleeve portion 9^a which receives the stock. This jaw 9 is movable toward and away from the fixed jaw 2, and the end thereof is longitudinally recessed or bifurcated to receive a block 10 which is pivotally mounted upon a pin 11. An integral pawl 12 is pendent from the block 10 and constructed to engage any selected one of a series of notches 13 in the adjacent face of the stock 1. A finger piece 14 projects from the swinging end of the pawl 12 and enables the pawl to be readily moved into inoperative

position when it is desired to release the movable jaw 9 to slide the same away from the fixed jaw 2. The upper end of the block 10 is formed with a flat side 10^a which is 5 flush with the gripping face of the movable jaw 9 when the pawl 12 is in engagement with one of the notches 13. It will thus be obvious that when an object such as the nut A is gripped between the two jaws the pawl 10 12 will be locked in operative position and can not be disengaged from the notch 13, since the necessary swinging movement of the pawl and block 10 is rendered impossible by the engagement of the flat side 10^a of 15 the block with the nut. This is indicated quite clearly by Fig. 2. A coil spring 15 is interposed between the upper end of the block 10 and the base of the bifurcation in the movable jaw, the ends of the coil spring 20 being received within suitable depressions 16 which serve to hold the spring in proper position, and the face of the spring normally serving to hold the pawl 12 yieldably in operative position. The movable jaw can 25 thus be moved freely toward the fixed jaw in order to obtain the desired adjustment, the pawl 12 sliding over the notches 13, although retrograde movement of the jaw is prevented by the pawl unless the same is 30 swung outwardly into an inoperative position. However, when an object such as the nut A is gripped between the jaws it is not possible for the pawl to be accidentally 35 swung into inoperative position and the movable jaw released, since this swinging movement of the pawl is prevented by the engagement of the flat side 10^a of the block 10 with the nut.

When operating upon a particular size of 40 nut or bolt it may be found desirable to lock the movable jaw 9 in an adjusted position. For this purpose the pawl 12 may be slotted at an intermediate point in its length to receive a disk 17, said disk being pivoted upon a pin 18, and the forward side thereof projecting through the front of the pawl where it is provided with a finger piece 19, while the rear side thereof is provided with a hooked arm 20 adapted to be 45 swung into and out of engagement with an undercut recess 21 formed in the base of the bifurcated portion of the movable jaw. The projecting portion of the disk 17 can be readily engaged by the fingers to rotate 50 the disk a sufficient amount to swing the hooked arm 20 into and out of operative position. When the hooked arm is in the 55 position indicated by full lines on Fig. 2 the locking device is inoperative and the pawl 12 can be swung outwardly and disengaged from the notches 13 when desired. However, when the hooked arm is swung 60 into engagement with the undercut recess 21, as indicated by dotted lines on Fig. 2, the pawl is locked in operative position and

the wrench can be used without danger of losing its adjustment.

Having thus described the invention, what I claim as new and desire to secure by Letters Patent, is:—

1. A wrench including a stock having a series of notches in one side thereof, a fixed jaw upon the stock, a movable jaw slidable on the stock and having the end thereof bifurcated, a block pivoted in the bifurcation of the jaw, a pawl rigid with the block and adapted to engage one of the notches of the stock to hold the movable jaw in an adjusted position, a finger piece projecting from the pawl, and a spring holding the pawl yieldably in operative position, the block being formed with a flat side which is flush with the gripping face of the jaw when the pawl is in operative position, and co-operates with an object gripped between the jaws to prevent accidental release of the pawl while the wrench is in use.

2. A wrench including a stock having a series of notches in one side thereof, a fixed jaw upon the stock, a movable jaw slidable on the stock and having a bifurcated portion, an undercut recess being provided at the face of the bifurcated portion, a pawl pivoted on the said bifurcated portion of the jaw and adapted to engage a selected one of the notches in the stock to hold the jaw in an adjusted position, and a hooked locking arm carried by the pawl and adapted to be swung into engagement with the before mentioned undercut recess to lock the pawl in an adjusted position.

3. A wrench including a stock having a series of notches in one side thereof, a fixed jaw upon the stock, a movable jaw slidable upon the stock and formed with a bifurcated portion having an undercut recess at the base thereof, a pawl pivoted within the bifurcated portion of the jaw and adapted to engage a selected one of the notches to hold the jaw in operative position, and a disk pivoted upon the pawl and arranged with a portion thereof projecting from the pawl, said disk being formed with a hooked arm which can be swung into engagement with the before mentioned undercut recess to lock the pawl in operative position.

4. A wrench including a stock having a series of notches in one side thereof, a fixed jaw on the stock, a movable jaw slidable upon the stock and having the end thereof bifurcated, the base of the bifurcation being formed with an undercut recess, a block pivoted in the bifurcated portion of the jaw, a pawl rigid with the block and adapted to engage a selected one of the notches in the block to lock the movable jaw in an adjusted position, said block being formed with a flat side which is flush with the gripping face of the jaw so as to co-operate with an object gripped between the jaws to

prevent release of the pawl while the wrench is in use, and a hooked locking arm carried by the pawl and adapted to be swung into engagement with the before mentioned undercut recess to lock the pawl in operative position.

In testimony whereof I have signed my

name to this specification in the presence of two subscribing witnesses.

HERMAN ALBERT WILL.
